(57) **CLAIM**

The ornamental design for a toilet seal, as shown and described.

DESCRIPTION

FIG. 1 is a top perspective view of a toilet seal illustrated in accordance with our ornamental design;

FIG. 2 is a bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof;

FIG. 8 is a rear elevation view thereof;

FIG. 9 is an exploded top perspective assembly view of the toilet seal of FIG. 1;

FIG. 10 is an elevated section view of the top plan view of FIG. 3 along section lines 10-10; and,

FIG. 11 is an elevated section view of the top plan view of FIG. 3 along section lines 11-11.

The broken line showing of parts of the drawings is included for the purpose of illustrating use and environment and forms no part of the claimed design.

1 Claim, 10 Drawing Sheets
